CLAIM

The ornamental design for a chair, as shown and described.

DESCRIPTION

FIG. 1 is a front perspective view of a chair showing my new design;

FIG. 2 is a rear perspective view thereof;

FIG. 3 is a side elevational view thereof; and

FIG. 4 is a bottom view thereof.

The side of the chair not shown is a mirror image of the side shown.

FIG. 1.

FIG. 2.

FIG. 3.

FIG. 4.
